UNITED STATES PATENT OFFICE

ELMER SEVERSON, OF DEERFIELD, WISCONSIN.

LOCKING CHAIN SNAP.

Application filed September 2, 1925. Serial No. 54,158.

To all whom it may concern:

Be it known that I, ELMER SEVERSON, a citizen of the United States, residing at Deerfield, in the county of Dane and State 5 of Wisconsin, have invented certain new and useful Improvements in Locking Chain Snaps, of which the following is a specification.

My invention relates to locking chain 10 snaps for tie chains for cattle and the like; and the objects of my invention are, first, to provide a rigid tubular frame with a clevis swiveled on a headed bolt secured within the rear end of the frame by a pin; second, 15 to provide a bifurcated latch with a downwardly projecting tang, adapted to be disposed through the bottom of the frame adjacent the front end thereof and locked there, by a slidable locking bolt actuated 20 by a spring; third, to unlock the latch by means of a key.

I attain these objects by the mechanism shown in the accompanying drawing in which—

- 25 Fig. 1, is a plan;
Fig. 2, is a side elevation;
Fig. 3, is the same side elevation partly in section on line 3—3 Fig. 1;
Fig. 4, is a transverse vertical section on 30 line 4—4 Fig. 2;
Fig. 5, is a transverse vertical section on line 5—5 Fig. 3;
Fig. 6, is a plan of the slidable locking bolt;
35 Fig. 7, is an end elevation of the same;
Fig. 8, is a side elevation of the same.

Similar numerals refer to similar parts throughout the several views.

The frame is sheet metal formed into a 40 square tube for a distance, then the top 1 is removed and the sides 2 rounded downward at the front end, and the bottom 6 pierced to permit the tang 3^a of a latch 4^a to pass downward through the same. A mortise 5^a 45 pierces the top 1 and bottom 6 in vertical alignment for inserting and operating a key 7, and a similar but shorter mortise is located adjacent the rear end for disposing a pin 8, which passes downward through a 50 groove in the side of a headed bolt 9 which connects a clevis 10 to the rear end of the

frame, and provides a means for attaching a chain 10^a. A locking bolt 11 is slidably disposed in the hollow of the frame and restricted in its movements by a screw 12 55 threaded through the bottom 6 and extending into a channel 13 in the bottom of the same, a similar channel 13^a is formed in the side of the bolt in vertical alignment with the mortise 5^a through which the key 7 60 passes in unlocking the latch 4^a. A spring 14 is disposed in the hollow of the frame, forward of the headed bolt 9, and between it and the slidable locking bolt 11, for keeping the bolt 11 pressed forward into the 65 notch 15 in the latch. The latch 4^a as will be seen by reference to Figs. 1 and 2, is composed of right and left members secured together in contact for a distance, thence diverging sufficient for one end of a chain 70 15^a to be inserted between them and secured to them by a pin 16, the members may be fastened together by rivets 17 or spot welded as desired, said latch is of even width for a distance, thence increased sufficient to 75 form the tang 3^a. To use this device, secure the latch to the end link of a chain, and attach the clevis to a link at a distance to form a loop of the desired size to pass around the animal's neck, so that when the 80 latch is secured to the frame the tie is complete. To lock the snap, remove the key and press the tang down through the mortise in the bottom plate 6, then the bolt 11 will seat in the notch 15 in the latch. To unlock, force the key 7 through the mortise 5^a 85 which will press the bolt 11 backward and release the latch.

Having thus described my invention, I 90 claim:

In a device of the kind described, a square tubular frame with the forward top portion removed and a mortise through the bottom plate adapted to receive the tang of a latch, a plurality of aligned mortises 95 through both top and bottom plates, one for admitting a key, and the other for disposing a pin for securing a headed bolt within the rear end of the frame, for revolvably mounting a clevis for attaching to 100 a chain, a latch with the outer end bifurcated for attaching a chain, and the inner

end provided with a notched tang adapted to seat in the mortise in the bottom of the frame, a slideable bolt disposed within the frame the rear end contacting a spring between it and the front end of the headed bolt, and the front end adapted to enter the notch in the latch, a channel in one side

of the bolt for admitting a key, and one in the bottom to receive a screw for restricting the forward movement of the same, in combination with a key for unlocking the latch. 10

In testimony whereof I affix my signature.

ELMER SEVERSON.
